UNITED STATES PATENT OFFICE.

WILLIAM L. OSBORNE, OF CHICAGO, ILLINOIS.

VALVE.

1,175,980.

Specification of Letters Patent. Patented Mar. 21, 1916.

Application filed September 5, 1912. Serial No. 718,606.

To all whom it may concern:

Be it known that I, WILLIAM L. OSBORNE, a citizen of the United States, and a resident of Chicago, in the county of Cook and State 5 of Illinois, have invented certain new and useful Improvements in Valves; and I do hereby declare that the following is a full, clear, and exact description thereof, reference being had to the accompanying drawings, and to the characters of reference marked thereon, which form a part of this 10 specification.

This invention relates to improvements in valves, and refers more specifically to that 15 type in which the valve piece is provided with an extension that fits into a reduced portion of the valve opening, in advance of the valve piece, to protect the valve seat and body seat from wear due to the wire drawing 20 action of the material passing through the valve when the valve is being opened and closed.

The invention refers more specifically to a novel removable facing member for the 25 valve piece on which the valve seat is formed, the manner of fastening the facing to the valve piece and to the construction wherein the body of the valve piece is adapted to serve as the valve closure in emergency 30 when the facing is removed.

The invention consists in the matters hereinafter set forth and more particularly pointed out in the appended claims.

In the drawings: Figure 1 is an axial section of a globe valve equipped with my improvements. Fig. 2 is a bottom plan view of the valve piece facing member. Fig. 3 is a detail section of the valve with the facing member removed, and with the body of the 40 valve piece arranged to constitute an emergency valve closure.

In the drawings, 10 designates the casing of an ordinary globe valve provided with the inlet and outlet branches 11 and 12, respectively, and with the interior diaphragm or partition 13 in which is formed the valve opening and which carries the body seat 14. Said body seat is herein shown as formed on the ring 15 which is screw-threaded in the 50 horizontal portion of the diaphragm or partition 13.

16 designates the valve piece which is movable toward and from the body seat 14, said valve piece having the usual swiveling connection with the screw-threaded stem 17 that extends outwardly and has screw-threaded

connection with the bonnet 18 of the valve casing.

The normal seating face of the valve piece is formed on the facing member 19 which is 60 removably applied to the lower side of the valve piece and is herein shown as formed to provide at its margin a conical seating face 20 to engage the tapered body seat 14. The said facing member 19 is shown as provided with a central opening 21 that fits over a downwardly extending stud 22 of the valve piece 16, and said facing member is clamped against the valve piece by means of an extension member 24 that is screw-threaded 70 to engage the lower screw-threaded end of the stud 22. Said extension member is made of a diameter to closely fit within the restricted portion of the valve opening formed in the ring 15 below the body seat 75 14, and is located at such distance in advance of the seating face 20 of the facing member that it enters said restricted opening in advance of the closing of the valve, and leaves said restricted opening only after the valve 80 is opened to a substantial extent. The said projection fits with a close slip fit within the restricted opening of the valve but the joint between the projection and the wall of the valve opening is not sufficiently tight to exclude the passage of fluid past the projection when the valve is open at the seat, the amount of fluid passing the projection at this time depending upon the operating pressure of the fluid. The projection prevents 85

the fluid from passing forcibly between the body seat and the seating face of the facing member when said parts are only slightly separated and therefore prevents the injurious effects of wire drawing of the fluid. 90

The said valve facing member is provided on its lower face, radially within the circumference of the extension 24 with an equalizing or pressure reducing chamber 25 which serves, when the valve facing is removed a distance from the body seat, either when opening or closing the valve, to reduce the pressure of the fluid passing through the valve and through the narrow space between the projection 24 and the reduced 95 opening circumscribed by the said ring 15, so as to thereby further reduce or minimize the wear due to the passage of the fluid across the valve and body seats, such as would occur if the chamber were not present. 100

Preferably, and as herein shown, the circumference of the projection 24 is located 105

radially within the outer side of the chamber, and the upper wall of the chamber is made of concave cross section so that when material is passing upwardly through the 5 valve, while the projection is within the restricted part of the valve opening, the jet issuing from the nozzle formed between the projection 24 and the reduced opening of the valve is given an inward, swirling motion so as to direct the same away from the 10 valve and body seats, thus further minimizing the wire drawing action of the material passing through the valve.

The inner or lower face 26 of the valve 15 piece is tapered on the same angle as the seating face 20 on the facing member 19 and the upper or outer side of the facing member is formed with a like tapered recess to fit over the tapered portion of the valve 20 piece. With this construction, if the facing member should become injured so as to require its replacement, the said facing may be temporarily removed and the seating face 26 of the body of the valve piece may 25 constitute the valve seating face for emergency purposes. If desired also, when the valve facing member is removed, the projection 24 may be retained, it being for such emergency use, spaced from the body of the valve piece 30 by a spacing ring 27. The said body of the valve piece is likewise formed, radially within the circumference of the projection 24 with an equalizing chamber 28 which serves the same function as the equalizing chamber 35 25 of the seating facing member, as clearly shown in Fig. 3 of the drawing.

The facing member 19 fits loosely about the stud 22 so that when clamped in position it will adjust itself to the body of the valve 40 piece and to the body seat in valve casing, regardless of slight inaccuracies of alinement or fit of the parts. Preferably the opening 21 of the facing member is made non-circular, or square so as to facilitate its 45 attachment in a grinding or polishing machine.

An advantage of the construction and arrangement of the facing member is that the main body of the valve piece may be made 50 of a metal of relatively low cost, while the facing member may be made of a metal that is determined by the use to which the valve is put. For instance, when the valve is used in high pressure work, the facing, as 55 well as the seat ring, will be made of very hard, wear-resisting material. When using the valve with corroding acids under low pressure, the facing member and seat ring will be made of a metal to resist the action 60 of the acids, though such metal need not be extremely hard.

Another advantage of the construction shown, is that, when the facing member is injured and requires to be removed, the 65 finished seating face of the valve piece,

which normally backs the facing member, may be temporarily used to close the valve and until another facing member is procured and applied. The application of the protecting projection 24 to the temporary 70 seating face enables the latter to be used with considerable economy even though it be made of relatively soft metal, as brass. Moreover, slight wear of the valve piece when thus used for emergency use does not 75 materially affect the same as a backing for the new facing member. In this connection it will be noted that the facing member is made of substantial thickness, it being a cast or forged piece, so that it is of substantial 80 strength to withstand the seating pressure brought thereon. Therefore, in case of a slight malformation of the body of the valve piece, due to the use thereof as a closure, the said seating member will not when forced 85 against the body seat follow the contour of said valve piece and thereby be distorted in a manner to produce a bad fit between the facing member and the body seat.

Another advantage of the construction described is that the facing member, confined in position, as it is, is free to adjust itself to the valve piece and the body seat when such parts are out of alinement or do not 90 present a true fit.

It will, of course, be understood that my improvements are capable of use with other valves than globe valves as illustrated, and further that the structural details disclosed are capable of variation within the spirit 100 and scope of the invention, and the invention is not limited to such details except as hereinafter made the subject of specific claims and as imposed by the prior art.

I claim as my invention:—

1. In a valve for the purpose set forth provided with a valve opening surrounded by a body seat, a valve piece provided with an integral seating face to engage the body seat, a removable and renewable member having a seating face to also engage the body seat and an annular surface to engage the integral seating face of the valve piece, and a single concentric extension at one side of the valve piece adapted to closely fit said valve opening to coöperate with the seating faces separately to protect said seating faces and body seat, for the purpose set forth.

2. In a valve for the purpose set forth, a valve piece provided with an integral seating face to engage a body seat and with a removable and renewable member having a seating face to engage the body seat, and a single concentric projecting extension in advance of the valve piece to coöperate with both of said seating faces, the renewable member being provided between its seating face and said projection with a pressure reducing chamber.

3. In a valve for the purpose set forth, a casing provided with a valve opening formed with a restricted portion, a valve piece provided with an integral seating face to engage a body seat and with a removable and renewable member having a seating face to engage the body seat, and a single concentric, circular projecting extension in advance of the valve piece, and removably secured thereto to constitute means to fasten the renewable member in place and to enter and closely fit the restricted portion of the valve opening.
4. A valve comprising a casing having a body seat, a valve piece movable toward and from the body seat, a facing member removably applied to the valve piece and provided with a seating face to engage the body seat, and a projection on the valve piece to enter and closely fit a restricted part of the valve opening in advance of the body seat to protect the said seating face and the body seat from the wire drawing action of the fluid passing through the valve, said valve piece being formed with a seating face to engage the body seat to close the valve when said facing member is removed.
5. A valve comprising a casing having a body seat, a valve piece movable toward and from the body seat, a facing member removably applied to the valve piece and provided with a seating face to engage the body seat, a projection on the valve piece to enter and closely fit a restricted part of the valve opening in advance of the body seat to protect the said seating face and the body seat from the wire drawing action of the fluid passing through the valve, said valve piece being formed with a seating face to engage the body seat to close the valve when the said facing member is removed and means whereby said projection may be applied to the valve piece in spaced relation to the seat thereof when the facing member is removed.
6. A valve comprising a casing having a body seat, a valve piece movable toward and from the body seat, a facing member removably applied to the valve piece and provided with a seating face to engage the body seat, and a projection on the valve piece to enter and closely fit a restricted part of the valve opening in advance of the body seat to protect the said seating face and body seat from the wire drawing action of the fluid passing through the valve, said valve piece being formed with a seating face to close the valve when said facing is removed, said facing member being provided between its seating face and said projection with a pressure reducing chamber, for the purpose set forth.
7. A valve comprising a casing having a body seat, a valve piece movable toward and from the body seat, a facing member removably applied to the valve piece and provided with a seating face to engage the body seat, a projection on the valve piece to enter and closely fit a restricted part of the valve opening in advance of the body seat to protect the said seating face and the body seat from the wire drawing action of the fluid passing through the valve, said valve piece being formed with a seating face to close the valve when said facing member is removed, said facing member being provided between its seating face and said projection with a pressure reducing chamber and the body seat being provided with a like chamber, said projection coöperating with the pressure reducing chambers of the facing member and body seat, for the purpose set forth.
8. A valve comprising a casing having a tapered annular body seat, a valve piece movable toward and from said seat and having a tapered seat to oppose the body seat, a removable facing member having at one side a tapered recess to engage over the tapered seat of the valve piece and provided at its other side with a tapered seating face to engage said body seat, said removable member being unconfined at its periphery, thereby permitting bodily adjustment of said member on the valve piece, and a projection removably fitted to the valve piece in advance of the valve piece to enter and closely fit a restricted part of the valve opening.
9. A valve comprising a casing having a body seat, a valve piece movable toward and from the body seat, a facing member removably applied to the valve piece and provided with a seating face to engage the body seat, a projection on the valve piece to enter and closely fit a restricted part of the valve opening in advance of the body seat to protect the said seating face and body seat from the wire drawing action of the fluid passing through the valve, and means coöperating with the projection to confine the facing member on the valve piece, said valve piece being formed with a seating face to close the valve when said seating face is removed, said facing member being provided between its seating face and said projection with a pressure reducing chamber.
10. A valve comprising a casing having a body seat, a valve piece movable toward and from the body seat, a facing member removably applied to the valve piece and provided with a seating face to engage the body seat, a projection on the valve piece to enter and closely fit the restricted part of the valve opening in advance of the body seat to protect the said seating face and the body seat from the wire drawing action of the fluid passing through the valve, and means coöperating with the projection to confine the facing member on the valve piece, said valve piece being formed with a seating face to close the valve when said facing member is removed, said facing member being provided between its seating face and said projection with a pressure reducing chamber.

close the valve when the said seating face is removed, said facing member and valve piece being provided radially within the circumference of the projection with pressure 5 equalizing chambers, for the purpose set forth.

11. In a valve for the purpose set forth, the combination with a valve piece having a seating face to engage a body seat, a re-
10 newable member having a backing surface engaging the seating face of the valve piece and itself having a seating face to engage the body seat, said member being provided

radially within the seating face thereof with an equalizing chamber, and centrally dis- 15 posed means whereby the removable member is attached to the valve piece.

In testimony, that I claim the foregoing as my invention I affix my signature in the presence of two witnesses, this 29 day of 20 August, A. D. 1912.

WILLIAM L. OSBORNE.
